CLAIM

The ornamental design for a set of bed sheets, as shown and described.

DESCRIPTION

FIG. 1 is a right side elevational view of the set of bed sheets showing my new design, the left side elevational view and the right side elevational view being identical;

FIG. 2 is a front elevational view, the rear elevational view and the front elevational view being identical;

FIG. 3 is top plan view, with the stitching, attaching the hook and loop attachments to the cover sheet being shown as broken lines.

FIG. 4 is a bottom plan view of the set of bed sheets with the rings being shown in broken lines, indicating that the rings are not to be considered part of the claim, but are present for environment purposes only; and,

FIG. 5 is an exploded view of the top sheet and the bottom sheet, demonstrating how the top sheet is aligned with the bottom sheet. The stitching, attaching the hook and loop attachments to the cover sheet are shown as broken lines. The hook and loop patches of the lower sheet are visible, and are shown.
